UNITED STATES PATENT OFFICE.

PAUL CARLTON ELLIOTT, OF LAWRENCE, KANSAS.

INTERNAL-COMBUSTION ENGINE.

1,230,286.

Specification of Letters Patent. Patented June 19, 1917.

Application filed October 19, 1916. Serial No. 126,504.

To all whom it may concern:

Be it known that I, PAUL C. ELLIOTT, a citizen of the United States, and a resident of Lawrence, in the county of Douglas and State of Kansas, have invented a certain new and useful Improvement in Internal-Combustion Engines, of which the following is a specification.

My invention is an improvement in internal combustion engines, and has particular reference to the construction and arrangement of the inlet and exhaust ports and the valves therefor for controlling the passage of the motive fluid to and from the engine cylinder.

An object of the invention is to provide rotary valves for the different ports arranged in a novel manner, each valve being constructed with the end in view of automatically grinding the same, increasing the possible valve opening, securing perfect timing due to the absence of the usual spring lag, and effecting thorough scavenging owing to the simplicity of construction.

The inventive idea involved is capable of receiving a variety of mechanical expressions, one of which for the purpose of illustrating the invention is shown in the accompanying drawings, wherein;

Figure 1 is a fragmentary section of an engine cylinder showing the valves therein and constructed in accordance with my invention;

Fig. 2 is a section on the line 2-2 of Fig. 1;

Figs. 3, 4, 5, 6, and 7 are diagrammatic sections showing the position of the pistons in the cylinders and the valves during a complete operation thereof;

Fig. 8 is another diagrammatic view showing in dotted lines, the position of one of the valves during a complete revolution of the crank shaft; and

Fig. 9 is a detail perspective view of the valves employed in connection with the invention.

There is illustrated in the accompanying drawings, what is now believed to be a preferred form of the invention, wherein the cylinder 10 has the usual piston 11 mounted therein. The cylinder 10 is provided with a head 12 having the oppositely disposed inlet and outlet ports 13 and 14 respectively, therein. The inlet port 13 opens into an inlet chamber 15 which extends into the head of the cylinder and said head is provided

with oppositely disposed inlet openings 16, which connect the inlet chamber with the explosive chamber of the cylinder. The cooling system includes a chamber 17 having a portion formed in the apex of the cylinder head 12 and has branches 18 which communicate with the remainder of said cylinder.

The inner walls of the cylinder head 12, 65 in longitudinal section, as shown in Fig. 1, are preferably arranged at right angles to each other to increase the valve area in a given bore, and mounted in bearings 19 in said cylinder head are the valve stems 20 of the rotary valves 21 for controlling the intake and exhaust. Each valve stem is provided upon its outer end with a beveled worm or spiral gear 22 with which meshes a suitable driving element for rotating said 75 gear and imparting a similar motion to the valve. The valve proper is preferably a flat circular plate having oppositely disposed openings 23, the outer ends of which communicate with the periphery of the plate, 80 said openings being adapted to register with the openings in the cylinder head which permit of the ingress and egress of the explosive charge and burnt gases to and from the interior of the cylinder. The inner faces 85 of the disks or plates of the valves preferably engage the inner walls of the cylinder head so that rotation of the valves will automatically grind the same, and owing to the formation of the said inner walls, the planes 90 of said disks or plates may be at right angles to each other and at the junction of said walls, the peripheries of the disks will be contiguous.

Referring now to Figs. 3 to 8, it will be seen that the invention is shown in connection with a four cycle engine, wherein one revolution of the crank shaft produces a quarter revolution of each valve, as shown in Fig. 8, and wherein, by reason of the peculiar construction of the valve, a maximum valve opening for the inlet and exhaust is produced. It is also to be noted that the efficiency of operation is greatly enhanced by dispensing with the usual spring in connection with the valves which generally causes lagging and consequent imperfect timing.

What is claimed is:

1. In an internal combustion engine, the combination with a cylinder having a head provided with intake and exhaust ports, an

- inlet chamber formed in said head and communicating with said inlet port, the head having oppositely disposed inlet openings connecting the inlet chamber with the explosive chamber of the cylinder, an exhaust chamber also formed in said head and having similar openings communicating with the explosive chamber, and valves for controlling the motive fluid in the cylinder.
2. In an internal combustion engine, the combination with a cylinder having a head provided with intake and exhaust ports, an inlet chamber formed in said head and communicating with said inlet port, an exhaust chamber also formed in said head, and rotary valves including disks mounted in said cylinder head and arranged at substantially right angles to each other for controlling the motive fluid in said cylinder.
3. In an internal combustion engine, the combination of a cylinder having a head provided with inlet and outlet ports and having the inner walls thereof arranged at an angle, and rotary valves mounted in said head and including disks, the planes of which are at an angle, and the peripheries of which are adjacent.
4. In an internal combustion engine, the combination of a cylinder having a head provided with inlet and outlet ports and having the inner walls thereof arranged at an angle, and rotary valves mounted in said head and including disks, the planes of which are at an angle.
5. In an internal combustion engine, the combination of a cylinder having a substantially conical head provided with intake and exhaust ports, an inlet and an exhaust chamber formed in said head and communicating respectively with the intake and exhaust ports, the inner walls of said cylinder head being arranged at an angle and having openings connecting the inlet and exhaust chambers with the explosive chamber of the cylinder, and rotary valves, including disks, mounted to turn on the inner walls of the cylinder head and having openings adapted to register with the openings in the cylinder head.
6. In an internal combustion engine, the combination of a cylinder having a substantially conical head provided with intake and exhaust ports, an inlet and an exhaust chamber formed in said head and communicating respectively with the intake and exhaust ports, the inner walls of the head being arranged at right angles to each other, and each provided with oppositely disposed openings, connecting the inlet and exhaust chambers with the explosive chamber of the cylinder, bearings in the cylinder head at right angles to each other, rotary valves engaging the inner walls of the cylinder head and each having oppositely disposed openings adapted to register with the corresponding openings in the cylinder head, the valves having stems extending through the bearings in the cylinder head, and means connected with the outer ends of the valve stems for rotating the valves.

PAUL CARLTON ELLIOTT.

It is hereby certified that in Letters Patent No. 1,230,286, granted June 19, 1917, upon the application of Paul Carlton Elliott, of Lawrence, Kansas, for an improvement in "Internal-Combustion Engines," an error appears in the printed specification requiring correction as follows: Page 2, lines 36-37, claim 5, and lines 51-52, claim 6, strike out the words "substantially conical;" and that the said Letters Patent should be read with this correction therein that the same may conform to the record of the case in the Patent Office.

Signed and sealed this 20th day of November, A. D., 1917.

[SEAL.]

R. F. WHITEHEAD,

Acting Commissioner of Patents.

Cl. 123—80.
